(57) **CLAIM**

The ornamental design for a wearable computer, as shown and described.

DESCRIPTION

FIG. 1 is a front perspective view of our new design for a wearable computer.

FIG. 2 is a front view of our new design for a wearable computer.

FIG. 3 is a back view of our new design for a wearable computer.

FIG. 4 is a top plan view of our new design for a wearable computer.

FIG. 5 is a bottom plan view of our new design for a wearable computer.

FIG. 6 is a right side view of our new design for a wearable computer; and,

FIG. 7 is a left side view of our new design for a wearable computer.

1 Claim, 5 Drawing Sheets
